DRIVING MECHANISM FOR PAPER-REFINING ENGINES.

No. 823,109.

Specification of Letters Patent.

Patented June 12, 1906.

Application filed December 9, 1901. Renewed February 21, 1905. Serial No. 246,776

To all whom it may concern:

Be it known that I, EBEN C. CROCKER, of Bridgeport, in the county of Fairfield and State of Connecticut, have invented a certain new and useful Driving Mechanism for Paper-Refining Engines, of which the following is a specification.

This invention relates to improvements in paper-refining machines, and particularly paper-refining machines comprising a stationary shell, an endwise-adjustable core rotating therein, and a driving mechanism for rotating said core, said shell and core being provided with coacting cutting-knives which while the core rotates comminute or grind up the material contained in the shell and which is to be used in the manufacture of paper. Serious defects exist in such machines, which I have discovered are due to the character of the driving mechanism employed for rotating the core and which I have also discovered may be remedied by the employment of the driving mechanism and the connections between it and the core constituting the present invention and which will presently be described in detail.

The driving mechanism heretofore employed consists of a belt-and-pulley construction connected with a suitable source of power and having its driven pulley splined or similarly connected with the shaft of the core, and owing to the lateral pull exerted by the belt on this driven pulley, and therefore on the core-shaft, the latter and the core are displaced laterally, so that the cutting-knives of the core do not coact uniformly at all points with the cutting-knives of the shell in grinding the stock, the working efficiency of the engine being thus materially lessened. Again, when the cutting-core and its shaft are thus displaced from their normal position a binding action takes place between them and their bearings which prevents the proper operation of the mechanism as a whole and particularly the mechanism for giving the core the endwise movement of adjustment heretofore referred to.

The present invention provides a driving mechanism for the core which, in addition to the advantages of simplicity in construction and effectiveness and durability in use, has the very important advantage that it avoids

entirely the lateral displacement of the core and its shaft and the defects just referred to resulting from such displacement.

In the drawing, which illustrates one embodiment of the invention, the figure is a side elevation, partly in section, of a paper-refining engine of the type referred to, showing the present improvements, certain parts of the construction being broken away for illustrative purposes.

Referring now to said drawing, *a* indicates a support or base, which may be of any usual or desired construction, but which in the best constructions is, as shown, of dimensions sufficient to support both the refining-engine and the driving mechanism. The refining-engine shown comprises the usual outer stationary shell *A*, supported in any suitable manner, as by standards, rising from the base *a*, and the usual cutting core or plug *a'*, which is mounted to rotate within the shell *A*. This cutting core or plug is mounted on a shaft *a''*, which, with the plug, is movable endwise or longitudinally to adjust the cutting-surface of the core relatively to the shell. The means for so adjusting the core and its shaft may be of any suitable form, such, for example, as the usual wheel or screw device shown at *A*². It will be understood that when so adjusted the core and its shaft will be held against endwise movement while rotating by this adjusting mechanism.

The driving mechanism employed comprises an electric motor of any form, size, and construction suitable for the purpose, and this driving-motor is connected with the shaft of the refining-engine, so that the drive of the motor on the plug-shaft shall be direct. The motor is, furthermore, so connected with the plug-shaft that the plug-shaft may be given the endwise or longitudinal movement before referred to relatively to the motor and its shaft.

The electric driving-motor is marked *B* in the drawing and is supported in any suitable manner, but is preferably supported, as shown, on the base *a*, which, as before stated, is of sufficient dimensions to accommodate both the motor and the refining-engine. The motor *B* is, furthermore, preferably arranged in substantially axial alignment with the shaft *a''* and the plug *a'* of the refining-engine, a

by thus mounting the motor its drive on the plug-shaft is direct and economy in power is secured.

The means for connecting the motor with the plug-shaft, so that the plug-shaft may have an endwise or longitudinal movement relatively to the motor, consists, preferably, of a coupling b' , which connects the contiguous ends of the plug-shaft a^2 and the motor-shaft b' , so that the said shafts rotate as one. One end of the coupling b' is rigidly fixed to one of the shafts a^2 b' and its other end is provided with a socket of angular cross-section which is adapted to receive the end portion of the other shaft, that end of the other shaft entering the coupling being similar in cross-section to the end of the coupling which it enters. This construction permits the latter shaft to move endwise in the socket without varying the rotation of the other shaft or moving the coupling endwise. As shown, the plug-shaft a^2 is a squared shaft, this shaft sliding in the coupling toward and away from the motor B as the plug-shaft is moved endwise or longitudinally by the adjusting mechanism, the coupling being rigidly secured on the motor-shaft b' ; though it is of course obvious that the coupling b' could be secured rigidly on the shaft a^2 and slide backward and forward on the shaft b' on the motor. The shafts a^2 b' are supported by the ordinary bearings of the motor and the refining-engine. If desired, however, an additional bearing b^2 may be provided arranged between the motor-frame and the refining-engine, which bearing is or may be supported on a bracket b^3 , rising from the base or support a .

What is claimed is—

1. In a refining-engine, the combination with a stationary shell of a cutting core or plug rotatably mounted within the shell, an endwise-adjustable shaft on which the plug is supported, mechanism for adjusting the plug

and its shaft endwise relatively to the shell and retaining them in such position of adjustment while rotating, an electric motor, and connections between it and said plug-shaft whereby the latter is rotated by the motor, substantially as described. 50

2. In a refining-engine, the combination with a stationary shell, of a cutting core or plug rotatably mounted within the shell, an endwise-adjustable shaft on which the plug is supported, mechanism for adjusting the plug and its shaft endwise relatively to the shell and retaining them in such position of adjustment while rotating, an electric motor arranged in substantially axial alinement with the plug-shaft, and connections between it and said plug-shaft whereby the latter is rotated by the motor, substantially as described. 55

3. In a refining-engine, the combination with a stationary shell, of a cutting core or plug rotatably mounted within the shell, an endwise-adjustable shaft on which the plug is supported, mechanism for adjusting the plug and its shaft endwise relatively to the shell and retaining them in such position of adjustment while rotating, an electric motor having a shaft arranged in substantial axial alinement with the plug-shaft, and a coupling connecting the contiguous ends of said shafts and permitting endwise movement of the plug-shaft relatively to the motor-shaft by the adjusting mechanism, substantially as described. 60

In testimony whereof I have hereunto signed my name, in the presence of two attesting witnesses, at Syracuse, in the county of Onondaga and State of New York, this 2d day of May, 1901. 70

EBEN C. CROCKER.
